UNITED STATES PATENT OFFICE.

MATTHEW WILLIAM WRAGG, OF AKRON, OHIO.

SASH LOCK.

Application filed September 20, 1924. Serial No. 738,869.

To all whom it may concern:

Be it known that I, MATTHEW W. WRAGG, a citizen of the United States, and a resident of Akron, in the county of Summit and State 5 of Ohio, United States of America, have invented a new and Improved Sash Lock, of which the following is a full, clear, and exact description.

This invention relates to fastening devices 10 and has particular reference to a window sash lock, the outstanding object of which is to provide an improved means for automatically locking a window sash in a partially open position for admitting air to the 15 room, and which further serves to prevent a further opening of the same to allow the entrance of a person from the exterior.

The invention furthermore comprehends a sash locking device of the character set 20 forth, which is extremely simple in its construction and mode of operation, which is inexpensive to manufacture and install, and which is thoroughly reliable and highly efficient in its purpose.

With the above recited and other objects 25 in view, the invention resides in the novel construction set forth in the following specification, particularly pointed out in the appended claim and illustrated in the 30 accompanying drawings, it being understood that the right is reserved to embodiments other than those actually illustrated herein to the full extent indicated by the general meaning of the terms in which the 35 claim is expressed.

In the drawings—

Figure 1 is a perspective view of the sash lock removed from the window.

Fig. 2 is a fragmentary horizontal sectional view showing the device in applied position.

Fig. 3 is a fragmentary vertical sectional view through a window equipped with a sash lock constructed in accordance with the invention and illustrating the normal position of the same when the sash is closed.

Fig. 4 is a similar view with the lock in operative position for locking the sash in partially open position.

Fig. 5 is a similar view with the locking device thrown to a position to permit of full opening of the sash.

Referring to the drawings by characters of reference, A designates a window frame, B 55 the lower sash mounted therein for vertical movement and including an upper

meeting rail C and a side rail D. The locking device constituting the invention and which is pivotally attached to the retaining and guide molding E of the window frame, comprises a body 10 having a substantially semicircular attaching lug 11 through which a fastening screw or other device 12 is inserted, said screw being anchored in the retaining and guide strip E. 60 The body 10 is provided respectively with an outwardly projecting arm 13 and a downwardly projecting arm 14 having right angularly disposed faces 15 and 16. The arm 14 is further provided with an eccentric or cam face 17. A weighted arm 18 extends inwardly and is provided at its free end with a ball-shaped terminal 19 constituting means for gravitationally swinging the member 10 to the position illustrated in Fig. 75 3. In this position the eccentric cam face 17 engages the inner upper corner of the meeting rail C and serves to lock the sash B in fully closed position. When it is desired to lock the sash B in a partially open 80 or raised position as illustrated in Fig. 4, the member is swung inwardly until the face 16 of the arm 14 is disposed in the same plane as the inner face of the sash B. This arrangement disposes the arm 13 in a position to intersect the path of movement of the upper rail C of the window frame so that the upper surface of the meeting rail C engages the face 15 of the arm 13 and thereby presents a further opening of the 85 sash B from the exterior, while admitting fresh air to enter the room. As illustrated in Fig. 5, the member 10 is manipulated to a position to swing the arm 13 inwardly so that the sash B is free to be moved to a fully 90 open position. The weighted arm 18 serves to normally throw the locking member 10 to a position when the window is fully closed for retaining the same against opening from 95 the exterior.

From the foregoing it will thus be seen that an extremely simple, yet highly effective sash locking device has been devised which permits of the locking of a window sash in a partially open position and against further opening from the exterior. It will be further noted that the device is easily installed and operates as an automatic means for locking the sash in fully closed position.

I claim:

A device of the character described comprising a pivoted member carried by one

side of the window frame, said member having an apertured semicircular lug, an attaching and pivoted member extending therethrough and anchored in the frame, a pair of right angularly disposed arms presenting respectively engaging faces for co-operation with the upper face of the meeting rail and the inner face thereof to lock the sash in a partially open position, against

further opening from the exterior, one of 10 said arms having an eccentric cam face, and a weighted arm projecting inwardly from said member for swinging said member to a position to engage the cam face with the upper inner edge of the meeting rail of 15 the sash to automatically retain the sash in fully closed position.

MATTHEW WILLIAM WRAGG.
